[57] CLAIM

The ornamental design for a copy machine top panel, as shown and described.

DESCRIPTION

FIG. 1 is a perspective view of a copy machine top panel showing my new design;

FIG. 2 is a top plan view thereof;

FIG. 3 is a right side elevational view thereof;

FIG. 4 is a front elevational view thereof;

FIG. 5 is a bottom plan view thereof;

FIG. 6 is a left side elevational view thereof; and,

FIG. 7 is a rear elevational view thereof.

The broken-line showing in FIG. 1 is for informational purposes only and forms no part of the instant design.

FIG. I

FIG. 2

FIG. 3

FIG. 4

FIG. 5

FIG. 6

FIG. 7
